UNITED STATES PATENT OFFICE.

JOSEPH M. GORDON, OF EUREKA, KANSAS.

MODE OF PROTECTING STORAGE STRUCTURES FROM LIGHTNING.

1,239,477.

Specification of Letters Patent. Patented Sept. 11, 1917.

Application filed July 8, 1915. Serial No. 38,810.

To all whom it may concern:

Be it known that I, JOSEPH M. GORDON, a citizen of the United States, residing at Eureka, in the county of Greenwood and State of Kansas, have invented a new and useful Mode of Protecting Storage Structures from Lightning, of which the following is a specification.

My invention relates to certain improvements in a mode of protecting metallic reservoirs and the like from the danger of ignition of their contents by electrical discharges and has for its object to provide an efficient protection of the class described which can be applied to the ordinary form of structure without changing the form of the latter.

A further object of the invention is to equip storage tanks having inflammable contents with sufficient electric conductors through which the electricity will be grounded, and thereby reduce possibility, of the same being struck by lightning, to a minimum.

In the accompanying drawings, which form a part of this specification, and in which like reference characters denote like parts:

Figure 1, is a perspective view of an oil-tank provided with my mode of protection,

Fig. 2, is a detail view showing one of the air terminals,

Fig. 3, is a detail of one of the bases for supporting the terminals.

In the drawings the numeral 1 designates a tank for the storage of petroleum, and while a cylindrical form of tank is shown I do not wish to limit the construction to that form as others may be found to be more advantageously adapted to the particular conditions found. Surrounding the tank, preferably at the top and bottom, I provide bands 2 of copper or other good conducting material, which are secured in close contact to the tank by the rivets or bolts. A plurality of conductors 4 formed of material like the bands extend up one side of the tank, across the top and down the other side to which they are secured by rivets 5 and are in electrical contact with said sides and top. The lower ends 6 of these bands are grounded below and adjacent to the sides of the tank. It will be noted that these

bands cross one another at the center 9 of the top of the tank.

Air terminals 10 or discharge points made of good conducting material are positioned around the outer edge of the top of the tank and one in the center where the bands cross. These terminals have their upper ends 11 pointed and are preferably nickelized to prevent corrodung. The lower end 12 is threaded and fits into an internally threaded portion 13 of a base 14. The said base is formed of good conducting material and is securely attached to the side and top of the tank and in electrical contact with the bands which extend around and over the latter. The number of the terminals to be used will depend upon the size of the tank or structure. While I prefer to construct the bands and terminals of copper the same is not essential as good results may be obtained by the use of iron.

From the above it is to be understood that the band and strap are snugly engaged with the tank, thereby being transported with the latter as a part of the tank. Furthermore the band and strap will in this way occupy only a minimum amount of space when the tank is set up.

Having described my invention, what I claim is:

1. A lightning protector for portable storage tanks including conducting bands snugly engaged with the outer periphery of the tank at the top and bottom of the latter, and conductive straps crossed over the top of the tanks and extending down the sides of the latter into engagement with said bands, the free terminals of said straps being grounded below the bottom of the tank.

2. A lightning protector for portable tanks including highly conductive bands snugly engaged with the tank, conductive straps mounted over the top of the tank and extended into engagement with said bands, the free terminals of said straps being extended below the lower end of said tank and grounded, and air terminals detachably mounted on said straps and bands.

J. M. GORDON.
